CLAIM

The ornamental design for a diffuser with crystal drawer, as shown and described.

DESCRIPTION

FIG. 1 is an isometric view of a diffuser with crystal drawer illustrating my new design;

FIG. 2 is a front elevation view thereof;

FIG. 3 is a back elevation view thereof;

FIG. 4 is a top plan view thereof;

FIG. 5 is a bottom plan view thereof;

FIG. 6 is a left-side elevation view thereof;

FIG. 7 is a right-side elevation view thereof;

FIG. 8, is an isometric view with the lid removed thereof; and,

FIG. 9 is a cross-sectional view of the section 9-9 shown in FIG. 2.

The broken lines showing a power button in FIGS. 1,2, and 8, supporting legs in FIGS. 2,3,5,6, and 7, a cord receptacle in FIGS. 3 and 5, a bottom square element in FIGS. 2,3,5,6, and 7, and two pill-shaped elements in FIG. 5 are for purpose of illustrating portions of the diffuser with crystal drawer that form no part of the claimed design. The broken lines showing crystals visible through the drawer in FIGS. 1,2,3,8, and 9 are for the purpose of illustrating environmental structure that form no part of the claimed design.
